TOY GIRAFFE OR THE LIKE

Reuben B. Klammer, 9460 Wilshire Blvd., Beverly Hills, Calif., 90212, and Robert Y. Allen and Melvin Shaw, Los Angeles, Calif.; said Allen and said Shaw assignors to said Klammer

Original design application July 13, 1967, Ser. No. 7,790. Divided and this application May 3, 1968, Ser. No. 11,766

Term of patent 14 years

Int. Cl. D21—02
U.S. Cl. D34—2

FIGURE 1 is a perspective view showing a toy giraffe or the like embodying our ornamental design; the side opposite being substantially a mirror image thereof; and

This application is a division of copending application Ser. No. D. 7,790, filed July 13, 1967, now abandoned.

We claim:

The ornamental design for a toy giraffe or the like, substantially as shown and described,
